United States Patent Office.

JAMES H. FOOTE, OF PITTSFIELD, MASSACHUSETTS.

Letters Patent No. 76,068, dated March 31, 1868.

IMPROVEMENT IN SLATE-FRAMES.

The Schedule referred to in these Letters Patent and making part of the same.

TO ALL WHOM IT MAY CONCERN:

Be it known that I, JAMES H. FOOTE, tinner, of Pittsfield, in the county of Berkshire, and State of Massachusetts, have made and invented a new and useful Slate-Pencil Case; and I do hereby declare that the following is a full, clear, and exact description of the construction and operation of the same, reference being had to the annexed drawings, making a part of this specification, in which—

Figure 1 is a perspective view of the case and face-lid.

Figure 2, a plan or elevation of the face-lid.

Figure 3, a plan of the case as cut before being bent.

Figure 4, an edge elevation of the spring.

Figure 5, a side elevation of the spring.

Figure 6, a perspective sectional view of the mortise-box and a portion of the frame.

Figure 7, a longitudinal section of the case and a portion of the frame, and

Figure 8, an isometric projection of a slate and frame with the pencil-case attached.

The object of my invention, which relates to a slate-pencil case, designed for school children and others who have occasion to make use of a slate and pencil, is to furnish a safe, cheap, and convenient place of deposit for the pencil when not in use.

The nature or principle of my invention consists in forming a mortise-box in the edge of either end or side of a slate-frame, and providing a short case, open at each end, which case is connected with the frame, and held in the mortise-box by a spring, in such a manner that either end of such case may be opened or drawn out of the mortise-box, and the pencil put in or taken out, when, by means of the spring, the case is again drawn back into the box and safely closed.

In carrying out my invention, I form a mortise or box, *b*, in the frame *a*, and make such box from four to six inches in length by one-fourth to one-half inch in width, and one-half to three-fourths of an inch in depth. I also make four small holes through the frame *a*, wherein I place the four wooden pins 1, 2, 3, and 4, arranged with reference to each other and to the mortise-box *b*, as seen in figs. 6, 7, and 8, the use of the pins being to retain the spring and case properly in the box *b*. And further, I construct and provide a case, *c*, first, by cutting and punching a sheet of tin or other metal, essentially as seen in fig. 3, then, by bending and soldering or otherwise attaching the same to the face-lid *d*, which I also make of tin or other sheet metal, by cutting and punching the same essentially as seen in fig. 2. And further, I provide a spring, *e*, of steel or other elastic material, which I make of the general form seen in figs. 4 and 5, that is to say, circular, with a short curve at each end, and this spring *e*, I pass through the case *c*, beneath the bar formed on the back side of such case by the lapping of the points, as seen in figs. 1 and 3.

Thus arranged, I place the spring and case in the box *b*, and pass a small pin or wire through the holes seen at either end of the face-lid *d* and case *c*, whereby the ends of spring *e* are borne backward, beyond the holes, in which are placed pins 1 and 4, on which pins the short curved ends of spring *e* catch, holding the case *c* in box *b*, and pressing the face-lid *d* snugly against the edge of the slate-frame *a*, as seen in figs. 7 and 8. I then insert pins 2 and 3, which pass through the slots or openings in the sides of case *c*, as seen in fig. 7, the object of pins 2 and 3 being to prevent the pulling out of the case beyond a given distance, and thus overstraining the spring *e*.

I prefer to make the face-lid *d* slightly wider than the thickness of the frame *a*, which is for convenience in opening the case, by seizing such lid between the thumb and finger.

It is to be observed that, by making the case open at each end, and by the peculiar form and arrangement of the spring *e*, I am enabled to put in or take out the pencil *f* at either end of such case, according to convenience or pleasure, it being necessary simply to draw out one end of the case and let the pencil slide in or out, as desired.

Having thus described the nature and construction of my invention, what I claim as new, and for which I desire to secure Letters Patent, is—

The case *c*, in combination with the double-acting spring *e* and mortised frame *a*, substantially as described and for the purpose specified.

JAMES H. FOOTE.
